THEODORE M. BRUBACK, OF DU BOIS, PENNSYLVANIA.

SOOT CLEANER FOR BOILERS.

Application filed August 28, 1926. Serial No. 132,218.

This invention relates to soot cleaners for boilers and aims to provide certain improvements therein.

Such soot cleaners usually comprise a cleaner element which is ordinarily a perforated pipe extending transversely across the bank of water tubes, such pipe being connected with a source of cleaning fluid such as steam from the boiler, and means being provided to turn the element either continuously in one direction or through a predetermined arc in reverse directions. The present invention relates to a cleaner of this general type in which the cleaner preferably oscillates, and in which the admission of cleaning fluid to the cleaner element is controlled by a valve which in turn is automatically opened and closed before and after the oscillation of the cleaner element. Customarily such operation is performed by hand, means being provided, such as a sheave and chain, which is manipulated by the operator during the cleaning periods.

The present invention is directed to a construction which is especially intended for use with high pressure boilers wherein the steam utilized for cleaning purposes is also at high pressure, although, of course, it may be used with other installations if desired. The device is designed to control unusual pressures without leakage at the valve or elsewhere, and at the same time to permit of easy and convenient operation.

To these ends the invention provides a construction in which all of the moving parts, with the exception of the controlling valve stem and valve disk, are arranged outside of the valve chamber so that they are not brought in contact with the cleaning fluid.

The invention includes various features of improvement which will be hereinafter more fully described.

Referring to the drawings, which illustrate one form of the invention,—

Figure 1 is a longitudinal section of the head of the cleaner with its associated elements, the device being shown in position attached to a boiler setting.

Fig. 2 is a transverse section of Fig. 1 on the line 2—2, Fig. 2^a being a detail.

Fig. 3 is a plan, partly in horizontal section, on the lines 3—3 in Figs. 1 and 2.

Fig. 4 is a plan of Fig. 1, showing some of the parts in horizontal section.

Fig. 5 is a transverse view taken in two planes, as indicated on the line 5—5 in Fig. 1.

Fig. 6 is a horizontal section on the line 6—6 in Fig. 2.

Fig. 7 is a section on the line 7—7 in Fig. 1.

Fig. 8 is a detail of L' and F².

Fig. 9 is a sectional view on the line 9—9 in Fig. 8.

Fig. 10 is a section on the line 10—10 in Fig. 4.

Referring to the drawings, let A indicate a boiler setting having the usual aperture B through which the cleaner element extends, a bushing C being usually provided for such aperture, and serving to support the device from the boiler setting. D shows the end of the usual cleaner element, the latter extending over the bank of tubes and being provided with appropriate orifices or nozzles, the cleaner element being connected by a union E with an elongated nipple F which extends into the cleaner head designated as a whole by the letter G. The head is provided with a chamber H into which the nipple projects and within which it is designed to rotate or oscillate, a stuffing box I being provided to prevent the escape of steam from the head around the end of the nipple. J is a steam passage connected with a pipe K which leads to the steam drum of the boiler or other source of cleaning fluid. Above the steam passage J is a valve chamber L, having a valve seat M and a valve disk N in axial alignment with the nipple F, the valve disk N being provided with a valve stem O by which the valve is operated. The valve disk N is swiveled on the end of its stem, so that the latter may rotate without necessarily imparting any rotary motion to the valve disk; hence the latter may close without any grinding action between the valve disk and seat. The valve stem O passes through a cover P bolted to the head, a stuffing box Q being provided to prevent the escape of steam around the stem.

The valve disk N as thus constructed controls the passage of steam into the cleaner element D. The valve is designed to be opened at such time as the soot cleaner is in operation and to be closed when the operation is completed. The opening of the valve is according to the preferred form of the present invention automatically effected just before the cleaning operation commences through whatever manual or other operative device is provided for turning the cleaner element. In the present construction there is illustrated the ordinary sheave wheel R which is adapted to be turned by pulling upon

a chain passing over the wheel, the latter being commonly used and being shown at R³. The sheave wheel hence effects two operations, one the opening of the valve disk N (and its subsequent closing) and the other the turning of the cleaner element.

Referring first to its control of the valve, the sheave wheel is mounted upon a shaft S which it is adapted to turn, the shaft carrying at its inner end a bevel pinion T which forms a part of a differential train mounted in a differential housing U. The idler element of the differential comprises three gears V (Figs. 1 and 5) mounted on the usual studs and the complementary bevel pinion, designated by the reference letter W. The differential housing U is provided with a gear Y shown in Figures 1, 2, 3, which is utilized to impart motion to the valve disk N so as to open and close the latter during the turning of the sheave-wheel R. For this purpose the gear Y is intermeshed with a gear A' carried on a counter-shaft B' arranged below the differential housing, which counter-shaft is carried in suitable bearings in the head and cover and has keyed to it a wide gear C' which meshes with a gear D' keyed on the valve stem O.

The result of this construction is that if the complementary differential pinion W is held stationary (by means hereinafter described) a rotation of the sheave wheel R and shaft S with its differential pinion T will cause the idler gears V to travel around the temporarily fixed gear W, thus rotating the differential housing U with its gear Y and through the intermediary of the countershaft B' and its gears rotate the valve gear D'. This rotation is utilized to open or close the valve disk N by means of the screw E' fixed to the valve stem O. The screw E' passes through the threaded part F' which for convenience is formed as a part of the cover P, the construction being best illustrated in Fig. 6. The gear C' on the countershaft B' is made sufficiently wide so that it remains in mesh with the gear D' on the valve stem O during the entire travel of the valve stem.

The effect of rotating the sheave wheel (to the left when the parts are in the position of Fig. 1) is to open the valve, and when the valve is fully open the mechanism then begins to rotate the cleaner element, it being preferable that the valve remain fully open during an oscillation of the cleaner element throughout a definite arc before the action of closing the valve commences. That is to say, the mechanism is designed to provide a given starting point when the valve is fully closed, this being the position in which the parts are left between successive uses of the apparatus. The first part of the movement of the sheave wheel opens the valve; a continued movement in the same direction rotates the cleaner element to the end of the arc for which it is set;

a reverse movement of the sheave wheel then rotates the cleaner element back to the opposite end of the arc and then the valve is closed.

The differential gear W is keyed to a short shaft G' which carries at its end a small pinion H' which meshes with a large gear I' keyed to the nipple F which is coupled to the cleaner element D. The large gear I' is formed with a lug J' best seen in Fig. 3, which lug engages a fixed lug K' on the frame, thereby preventing the gear I' from turning to the right. During the time when the valve is being initially opened a locking lever L' engages the opposite side of the lug J' and prevents the gear I' from turning to the left. These parts in effect constitute the locking mechanism for the differential gear W. This locking mechanism holds the gear I' against rotation until the valve is fully opened. The locking lever is, however, released at the fully open position of the valve by means of a traveling nut M' which moves along a screw thread formed on the left-hand end (Fig. 1) of the shaft B', the nut engaging a projection N' on the locking lever just before the valve is fully opened and moving the latter so that it disengages the lug J' of the gear I' immediately after the valve is completely opened. As soon as the lug J' is disengaged, the short shaft G' may rotate the gear H' by means of the gear W, and this rotation continues so long as the sheave R is moved to the left and until the large gear I' reaches the predetermined end of the arc, during which movement the cleaning fluid projects itself under pressure from the nozzles in the cleaner element D. This prescribed arc may be varied as desired by means of a stop O' which is shown as bolted to the gear I' at any part of its periphery which may be selected, and when this stop O' contacts with a complementary stop P' fixed on the frame of the device, as shown in Figs. 2 and 2^a, further movement of the gear I' and cleaner element in that direction is prevented.

At this point in the operation the sheave wheel R is stopped, and the operator then grasps the opposite branch of the operating chain and reverses the movement of the sheave wheel, the latter then turning to the right.

At the beginning of the reverse movement the gear I' is free to reverse its direction of movement and so also is the valve stem O, the rotation of which has been stopped by the contact of the gear D' against the threaded part F'. This contact, however, stops the valve stem from rotating only in one direction and the reversal of the sheave would tend to move the valve to the left in Fig. 1 toward the closing position. It is desirable, however, that, as before stated, the valve be maintained fully open until the cleaner element has been rotated back to its starting position and in order to effect this a

catch is provided which engages the differential housing and prevents its rotation, thereby avoiding the transmission of movement through gear A', shaft B' and gear C' and D' to the valve stem O.

This catch is shown as comprising a bolt Q' which is adapted to be moved in bearings in the frame, the bolt being normally urged to the left in Fig. 1 by a spring R'. The end 10 of the bolt is designed to engage one of a series of projections S' formed at the rear of the differential housing and best seen in Fig. 7. While it is not strictly essential that the bolt Q' should hold the differential housing against movement except during a major part of the reverse rotation of the sheave, it is best constructed so as to hold the housing at all times other than the period in which the valve is designed to operate, namely, 15 when the cleaner element D is at or near its position of rest. The bolt hence is constantly urged forward into contact with one of the stops S' on the differential housing until it is forcibly pushed back by a camming lever T', 20 the latter being best seen in Figs. 3 and 4. The camming lever T' is pivoted on the frame and is connected with a cross bar U' which in turn is connected with a cross bar V' passing through the bolt Q' by links W' W'. 25 Normally the camming lever T' occupies its forward position during the operation of the cleaner element but when the latter approaches its inactive position on its reverse stroke the lug J' contacts with a cam face Y' 30 on the camming lever, thus forcing the latter to the right and pushing the bolt Q' out of engagement with the lugs S'. As seen in Fig. 3, which illustrates the position of the parts at the end of the unlocking movement 35 of the bolt, the nose of the camming lever rests upon the lug J' during the time when this lug is prevented from moving to the right by the stationary lug K'. In this position the gear I' and cleaner D being locked 40 against movement to the right so that the differential gear W is fixed against rotation, the differential housing is released and a continued movement of the sheave to the right then rotates the countershaft B' and the valve 45 stem O so that the valve commences its closing movement. When the valve is fully closed, the sheave is thereby held against movement to the right, in which position it remains until it is again desired to operate 50 the device. The valve by this mechanism can be closed with whatever force is desired. During the closing movement of the valve the nut M' which has continuously held the locking lever L' in its inactive position, as shown 55 in Fig. 4, travels to the left in Fig. 1, thereby releasing the locking lever so that at the beginning of the closing movement of the valve the locking lever has moved under the influence of a spring Z' (Figs. 3, 4 and 10) 60 to the position of Fig. 3 where it prevents 65

movement of the gear I' and the cleaner element to the left until the valve is again opened to the required extent by a movement of the sheave to the left, during the final part of which valve opening movement the nut M' 70 again releases the locking lever and permits the operation of the cleaner element to commence.

The invention best includes certain details of construction which facilitate the operation of the parts. Thus, the usual cover plate or washer A² is preferably provided, as shown in Fig. 1, around the nipple F so as to avoid as far as possible the escape of steam or fire gases out through the boiler setting, such cover plate being preferably urged forward by a string B² against a flange C² on the plate D² forming a part of the bushing C. A ball bearing E² is provided surrounding the nipple F whereby the end of the cleaner D is supported in a manner to produce as little friction as possible. The nut M' is preferably formed with a wing F² which slides on a guide rod G², as best seen 80 in Figs. 8, 9 and 10. 85

The operation of my invention may be gathered from the foregoing description. Fig. 1 represents the positions of the parts when the mechanism is at rest, the valve disk N being closed and the cleaner element D being in position where it is ready to begin the cleaning operation. When it is desired to clean the boiler the operator grasps the left-hand branch of the chain, pulling the same and rotating the sheave wheel to the left. If by mistake the operator pulls on the right-hand branch of the chain, the sheave wheel will not move, since all parts of the differential are locked against movement. This is due to the stop K' preventing movement of the gear I' and shaft S to the right, and the movement of the valve disk N being checked by its seat, so that the housing cannot move to the right. 95 100 105

Upon the initial movement of the sheave 110 to the left, the gear wheel I' is prevented from turning to the left by catch L' engaging the lug J' so that the only movement possible is the rotation of the differential housing which through the countershaft B' and connected gearing opens the valve. Until the valve is fully opened the cleaner mechanism is positively held against movement in either direction and if it were desired the sheave wheel could be turned first in one direction and then in another to partially open and close the valve without moving the cleaner element from its position of rest. But upon a continued movement of the sheave 115 wheel to the left, the valve becomes fully opened until its pinion D' reaches the threaded part F' when all movement of the valve in that direction is stopped. Simultaneously the catch lever L' is moved out of the path of the lug J' on the gear wheel I' by 120 125 130

the nut M' ; thereupon the cleaner element is rotated to the left, thus discharging the steam jets over the surfaces to be cleaned, and this operation continues until the stop O' reaches the stop P' . In the meantime the stop J' has been moved off the nose of the camming lever T' , thus releasing the locking bolt Q' so that it engages one or the other of the projections S' , thus preventing the valve from closing 10 when the operator grasps the opposite branch of the chain and moves the cleaner element back to the point of beginning, the valve thus remaining open during the entire cleaning oscillation. As the element approaches its 15 starting point the lug J' moves the camming lever T' to right (Fig. 1), thus releasing the bolt Q' ; and immediately after the lug J' contacts with the stop K' , thus preventing further movement of the gear I' to the right, 20 and locking the differential gear W' so that further movement of the sheave to the right results in the forward movement of the valve toward its seat.

If desired, after the return stroke of the 25 cleaner element has been completed, the sheave wheel R' can be turned to the left and the cleaner element will repeat its movement to the left as the lug J' is not locked by locking lever L' until after the valve has 30 started to close. If this mode of operation is desired the cleaner element may be oscillated as many times as is desired and finally when the operator wishes to do so, he may return it to its initial or starting position and then 35 close the valve.

While I have shown and described one form of the invention, it will be understood that I do not wish to be limited thereto, since various changes may be made therein without departing from the spirit of the invention. Preferably, however, the entire mechanism for controlling the valve and turning the cleaner element is located outside of the steam passages so that none of such mechanism is directly affected by contact with the steam. This provides an apparatus which is well adapted for high pressure steam boilers and the like.

What I claim is:—

- 50 1. In a soot cleaner, a cleaner element, a conduit for cleaning fluid, a valve controlling admission of said fluid to the cleaner element, and means for operating the valve and turning the cleaner element comprising a differential gear train.
- 55 2. In a soot cleaner, a cleaner element, a conduit for cleaning fluid, a valve controlling admission of said fluid to the cleaner element, means for operating the valve and turning the cleaner element comprising a differential gear train, said differential gear train having one of its elements connected to the valve and adapted to operate the same and having another of its elements connected to the cleaner element and adapted to operate the

same, and means for preventing the movement of parts of said differential gear train to bring one or the other of said gear elements into operation.

3. In the soot cleaner of claim 2, a stop for 70 the valve mechanism adapted to prevent movement.

4. In the soot cleaner of claim 2, the means for preventing movement of parts of the differential gear train comprising a stop for 75 controlling the movement of the valve and a stop for controlling the movement of the cleaner element.

5. In the soot cleaner of claim 2, the differential element which controls the valve being the part carrying the idler gears of the differential gear train and the element which controls the cleaner element being the driven gear of the differential.

6. A soot cleaner having a cleaner element, 80 a conduit for cleaning fluid connected therewith, a valve for controlling the passage of said fluid into said cleaner element, a gear for rotating said cleaner element, a countershaft for operating said valve, a differential gear 85 train for turning said countershaft and said gear, an operating shaft for said differential gear, a shaft in alignment with said operating shaft having a pinion for turning said gear fixed to said cleaner element.

7. The soot cleaner of claim 6, in which the gear of the cleaner element is provided with a lock and said countershaft is provided with a nut for operating said lock.

8. A soot cleaner having a cleaner element, 100 a conduit for cleaning fluid, a valve for controlling the passage of said cleaning fluid into said cleaner element, and means for operating said valve and turning said cleaner element, comprising a differential gear connected with the valve and cleaner element and a lock for holding the casing of said gear stationary during the operation of said cleaner element, and means for releasing said lock to permit closing of said valve at the end of the 105 movement of said cleaner element.

9. In the soot cleaner of claim 8, a releasing means comprising a cam operated by said cleaner element.

10. A soot cleaner comprising a cleaner element, a conduit for cleaning fluid, a valve for controlling the passage of cleaning fluid to said element, a stem located outside of said conduit and cleaner element and provided with a thread, a fixed nut engaging said thread, a countershaft located outside of such steam passages, an operating shaft, a differential gearing adapted to drive said countershaft, a pinion also driven by said differential gearing, a gear on said cleaner element driven by said pinion, means for alternately operating said valve and cleaner element, all of said parts with the exception of said valve and its seat located outside of said cleaner element and said conduit.

11. A soot cleaner having a cleaner element, a valve, means for operating said valve and turning said element, comprising a differential gear, a bolt adapted to engage the housing of said differential gear and hold the same in fixed position, a cam lever for operating said bolt, a pinion driven by said differential gear, a gear connected to said cleaner element and driven by said pinion, a locking lever for said last-named gear, a countershaft driven by said differential gear and operating said valve, and a travelling nut for operating said locking lever.

In witness whereof, I have hereunto signed my name.

THEODORE M. BRUBACK.
